[57] CLAIM

The ornamental design for a lounge chair, as shown and
described.

DESCRIPTION

FIG. 1 is a perspective view of the lounge chair showing
my new design;

FIG. 2 is a left side elevational view thereof;

FIG. 3 is a front elevational view thereof;

FIG. 4 is a rear elevational view thereof;

FIG. 5 is a top plan view thereof; and

FIG. 6 is a rear perspective view thereof.

The right side elevational view of the subject lounge
chair not shown in the drawings is a mirror image of the
left side elevational view shown in FIG. 2.
